UNITED STATES PATENT OFFICE.

EDWARD C. HURLBERT, OF ST. JOHNS, OREGON.

STOOL.

1,111,586.

Specification of Letters Patent. Patented Sept. 22, 1914.

Application filed December 14, 1912. Serial No. 736,796.

To all whom it may concern:

Be it known that I, EDWARD C. HURLBERT, a citizen of the United States, residing at St. Johns, in the county of Multnomah and State of Oregon, have invented certain new and useful Improvements in Stools, of which the following is a specification, reference being had therein to the accompanying drawing.

10 This invention relates to furniture and has special reference to a folding and telescopic stool or seat arranged to be carried in a pocket when collapsed.

15 The principal object of the invention is to improve and simplify the general construction of devices of this character.

The second object of the invention is to provide an improved seat arranged for such a stool.

20 With the above and other objects in view, this invention consists in general of certain constructions, combinations and arrangements of parts, as will be hereinafter fully described, illustrated in the accompanying drawings, and specifically claimed.

In the accompanying drawings, like characters of reference indicate like parts in the several views, and:—Figure 1 is a perspective view of the seat in position for use. Fig. 2 is a plan thereof. Fig. 3 is a side elevation thereof. Fig. 4 is a vertical section therethrough. Fig. 5 is a section similar to Fig. 4 showing the parts collapsed or folded. Fig. 6 is a side elevation of the device with the parts collapsed. Fig. 7 is an enlarged detail view on the line 7—7 of Fig. 4. Fig. 8 is an enlarged detail view showing the manner of attaching the corners of the seat. Fig. 9 is a section taken on line 9—9 of Fig. 8.

40 In carrying out the objects of this invention there is provided a tubular stem 10 wherein is a slidable second tubular portion 11 which is arranged to be held in adjusted position by means of a set screw 12. Slidable in the lower end of the portion 10 is a plunger 13 provided with eyes 14 in its lower surface. To these eyes 14 are attached feet 15 which, when the device is extended, may be folded outwardly as is indicated in Fig. 4. Extending into the plunger 13 is a screw 16, the body of which moves in a slot 17 having portions 18 arranged at right angles at each end so that the member 11

may be held either in collapsed or extended 55 position. Movable in the member 11 is a plunger 19 carrying eyes 20 to which are secured arms 21 having reduced conical ends 22 which fit into reinforced pockets 23 projecting at the corners of a seat 24 consisting of an air-tight, flat bag provided with an inflation valve 25. By referring to Figs. 8 and 9 it will be seen that the top and bottom of the seat 25 pass over and fit upon the upper portion of the arms 21, so as to 60 allow the arms to support the seat without allowing the escaping of air at the corners of the seat, since the arms do not puncture the seat 25 but support the same at the reinforced pockets 23. The corners or edges 65 of the seat may be stitched together so as to hold the seat together and prevent the escaping of air therefrom. Extending into the plunger 19 is a screw 26 which moves in a slot 27 in the member 11, the slot being 70 provided at its upper end with an angularly extending portion 28 so that when the device is expanded, the seat may be held in a 75 raised position.

When using the device the telescopic sections are extended and locked in the extended position by means of the screw 12. Then the feet are drawn out by properly moving the screw 16 and locked in expanded position. Next, the plunger 19 is moved upwardly which allows the arms 21 to fall outwardly and stretch the seat 24. Finally, the seat 24 is inflated by blowing or pumping air through the valve 25. In collapsing the device, the reverse of this operation is performed.

There has thus been provided a simple and efficient device of the kind described, and for the purpose specified.

Having thus described the invention, what 95 is claimed as new, is:—

A stool comprising a support, diverging arms carried by said support, said arms slanting upwardly and terminating in tapering ends, of an inflatable rectangular seat 100 carried by said arms, said seat composed of an upper and lower layer of cloth, said layers of cloth positioned upon the upper sides of said arms, said layers secured together at their edges and fitting together at their corners, thereby forming a non-inflatable flexible portion at each corner, said non-inflatable flexible portions fitting snugly upon the 105

tapering ends of said arms; and a conical reinforcing sleeve fitting over each tapering end of each arm and over the flexible portions of said seat which engages the tapering end, whereby the seat will be held securely in engagement with said arms without danger of puncturing the same.

In testimony whereof I hereunto affix my signature in presence of two witnesses.

EDWARD C. HURLBERT.
